UNITED STATES PATENT OFFICE.

JOHN F. A. HOORT, OF NEW YORK, N. Y.

DESIGN FOR A MANTEL.

SPECIFICATION forming part of Design No. 24,154, dated March 26, 1895.

Application filed January 10, 1895. Serial No. 534,496. Term of patent 3½ years.

To all whom it may concern:

Be it known that I, JOHN F. A. HOORT, a citizen of the United States, residing at New York, in the county of New York and State of New York, have invented and produced a new and original Design for Mantels; and I do hereby declare the following to be a full, clear, and exact description of the same, reference being had to the accompanying drawing, forming a part thereof.

The figure of the drawing is an isometric view of the mantel.

The leading feature of the design for a mantel consists in the design for the frame 15 and its ornamental adjuncts surmounting the mantel shelf.

Numerical 1 denotes the mantel shelf which resembles an entablature supported by columns 2. The frieze is represented as having a comparatively large vertical extent and its lower part has a crenelated ornamentation 4 situated immediately above and overhanging a row 5 of small rectangular panels. Beneath these panels is an ovolو 6. The entablature 25 rests immediately upon plinth like blocks 7 which are connected to plain columns 8 having at their feet bases 9 between which and the blocks 7 are situated the columns 10. The rear plain columns 8 are ornamented on

their inner front edge with a beading and an ovolو which ornamentation also extends between the columns immediately under the entablature.

11 is a skirt extending from the rear edge of the mantel shelf to the foot of the columns 35 and constituting a background.

Above the mantel shelf are two entablatures 12 and 13 of the same height but of unequal length the longer being shown at the rear of the other and supported at each end 40 by columns 14 of rectangular form. The front one of these entablatures is represented as supported at each end by a cylindrical column 15 of the Doric order situated immediately in front of the inner one of the two rectangular columns above referred to. Said latter columns are connected by a frame 16 and the space at the rear of said columns on each end is closed by a panel or back 17.

What I claim is—

The design for a mantel as herein shown and described.

In testimony whereof I affix my signature in presence of two witnesses.

JOHN F. A. HOORT.
